UNITED STATES PATENT OFFICE.

OWEN DAVID LUCAS, OF WESTMINSTER, LONDON, ENGLAND.

GAS-PRODUCER.

1,153,506.

Specification of Letters Patent. Patented Sept. 14, 1915.

Application filed March 27, 1915. Serial No. 17,532.

To all whom it may concern:

Be it known that I, OWEN DAVID LUCAS, a subject of the King of Great Britain, residing at 39 Victoria street, Westminster, London, England, have invented new and useful Improvements in Gas-Producers, of which the following is a specification.

This invention relates to improvements in gas producers, more especially those intended to be used with fuel containing a high percentage of water, such as peat.

According to this invention fuel, such as peat which may contain 70% or more of water, is introduced into a producer provided with an upward draft. The fuel is fed to the top of the producer through a long pipe, which may be provided with a rotating worm, or this pipe may be inclined and itself rotated. The pipe or the worm terminates in a hopper above the producer and is so arranged that the peat fuel drops into the producer through an air locked feeding device. The feeding device may itself be an extension of the worm or tube, and rotating with it. A pipe leading from the fuel feeding pipe at a point near the air locked feeding device connects the fuel feeding pipe to the under side of the producer. In this pipe is a fan which draws air through the open end of the fuel feed pipe and delivers it to the producer hearth thus forming the air blast.

The pipe forming the gas outlet from the producer surrounds the fuel feed pipe. In the case of a horizontal feed pipe provided with a worm this gas pipe is preferably not concentric with the feed pipe but is inclined at an angle so that its lower end is farther from the producer, thus forming a tar trap; or in the case where the feed tube itself is inclined the gas pipe may be concentric with it and may be provided with tar traps to prevent condensation products returning to the producer.

It will be seen that by these arrangements the hot gases from the producer impart to the fuel in the feed pipe some of their heat and part of the water in the fuel is evaporated and the steam thus formed mixes with the air sucked in by the fan, so that the blast for the producer is mixed with the moisture obtained from the fuel. In order to regulate the amount of steam in the air blast for varying contents of moisture in the fuel the blast pipe is provided with a valve or system of valves so arranged that

the amount of air and moisture sucked through these may be reduced and free air from the atmosphere drawn in when desired.

The drawings illustrate apparatus made in accordance with this invention.

Figure 1 is a side elevation partly in section. Fig. 2 is a section in the line 2-2 Fig. 1. Fig. 3 shows a modification in which the feed tube revolves.

a is a gas producer having a hearth *b* of ordinary construction.

c is a fuel feed hopper leading to a feed tube *d*, within which is a feed worm *e*. The feed worm *e* is driven by means of a bevel wheel *f* gearing with another bevel wheel *g* on a driven shaft *g'*. The end of the fuel feed tube *d* communicates with an air locked hopper *h* of ordinary construction which is operated by means of a handle *h'*, and an air supply pipe *i* leads from the end of the tube *d* to an air pump *j* and thence to another pipe *k* which delivers air to the hearth *b*. In the pipe *i* is a regulating valve *i'* and communicating with the pipe *i* is another pipe *l* opening to the atmosphere and having in it a regulating valve *l'*.

m is an outlet for the produced gases which leads to a pipe *n* concentric with the feed tube *d* and communicating with a main pipe *o*. In the pipe *n* is a scraper *n'* which is revolved by means of a toothed wheel *n''* gearing with a pinion *n³* on a shaft *n⁴* upon which is another toothed wheel *n⁵* gearing with a pinion *e'* on the shaft of the worm *e*.

In operating the producer the air is drawn through the incoming fuel in the feed tube *d* and passes through the pipes *i* and *k* to the hearth *b*. The hot gases issue from the outlet *m* and passing through the pipe *n* impart some of their heat to the incoming fuel; steam thus formed is mixed with the blast. The flow of the mixture of air and moisture or steam is or may be regulated by the valve *i'*. The valve *l'* regulates any additional amount of air supplied to the blast current delivered through the pipe *l*. In this way the relative proportions of air and steam delivered to the producer may be varied. Any tar that may be deposited in the pipe *m* is fed down by the scraper *n'* and runs into the tar trap *p* from which it is drawn off by the valve *q*.

In the modification, as shown in Fig. 3, the fuel feed tube *d* is rotated by means of a toothed wheel *e²* gearing with a pinion *e³* on a shaft upon which is also a bevel wheel

gearing with another bevel wheel g' on a driven shaft g^2 . The scraper n' is revolved by means of a toothed wheel n^2 gearing with a pinion n^3 on a shaft n^4 upon which is another pinion n^5 gearing with the toothed wheel e^2 .

What I claim is:—

1. In combination with a gas producer for the use of fuels containing moisture a feed pipe for the moist fuel, a pipe connected with the producer and surrounding the feed pipe for conveying hot gases from the producer to a space between the fuel feed pipe and said surrounding pipe and thus heating it, means for drawing air through the fuel feed pipe and thus saturating the same with moisture during its passage through the fuel pipe, an air locked feeding device between the fuel pipe and the producer, and a pipe for conveying moisture-laden air from the discharge end of the fuel feed pipe.
2. In combination with a gas producer, a fuel feed pipe, a feed worm in the fuel feed pipe, means for rotating the feed worm, another pipe for conveying the outgoing gases surrounding the fuel feed pipe, a scraper in the said pipe, means for rotating the scraper, means for drawing air through the fuel feed pipe, and an air locked feeding device between the fuel feed pipe and the producer.
3. In combination with a gas producer, a fuel feed pipe, a feed worm in the fuel feed

pipe, means for rotating the feed worm, another pipe for conveying the outgoing gases surrounding the fuel feed pipe, a scraper in the said pipe, means for rotating the pipe, means for drawing air through the fuel feed pipe, and an air locked feeding device between the fuel feed pipe and the producer.

4. In combination with a gas producer, a fuel feed pipe, a feed worm in the fuel feed pipe, means for rotating the feed worm, another pipe for conveying the outgoing gases surrounding the fuel feed pipe, a scraper in the said pipe, means for rotating the scraper, means for drawing air through the fuel feed pipe and leading it to the hearth of the producer, and an air locked feeding device between the fuel feed pipe and the producer.

5. In combination with a gas producer, a fuel feed pipe, a feed worm in the fuel feed pipe, means for rotating the feed worm, another pipe for conveying the outgoing gases surrounding the fuel feed pipe, a scraper in the said pipe, means for rotating the pipe, means for drawing air through the fuel feed pipe and leading it to the hearth of the producer, and an air locked feeding device between the fuel feed pipe and the producer.

OWEN DAVID LUCAS.
